UNITED STATES PATENT OFFICE.

CLARK T. HENDERSON, OF MILWAUKEE, WISCONSIN, ASSIGNOR TO THE CUTLER-HAMMER MFG. CO., OF MILWAUKEE, WISCONSIN, A CORPORATION OF WISCONSIN.

SWITCH.

1,342,674.

Specification of Letters Patent. Patented June 8, 1920.

Application filed April 25, 1916. Serial No. 93,408.

To all whom it may concern:

Be it known that I, CLARK T. HENDERSON, a citizen of the United States, residing at Milwaukee, in the county of Milwaukee and 5 State of Wisconsin, have invented new and useful Improvements in Switches, of which the following is a full, clear, concise, and exact description, reference being had to the accompanying drawing, forming a part of 10 this specification.

This invention relates to electric switches and more especially to those of the laminated brush type.

In such switches the brush contacts are 15 commonly employed to coöperate with flat contact plates and to engage the same with a wiping action which subjects both to severe wear and the contact plate to a cutting action by the ends of the brush laminæ.

20 The present invention has among its objects to provide for lubrication of the contact surface impinged by the brush to thereby minimize the aforesaid wear and cutting action and further to provide for lubrication of the brush laminæ.

In the accompanying drawing wherein is illustrated one embodiment of the said invention,—

Figure 1 is a side view of a set of switch 30 contacts provided with one form of lubricating means, and

Fig. 2 is an enlarged perspective view of the brush and lubricating means shown in the preceding figure.

35 Referring to the drawing a brushholder 1 is supported upon a panel 2 and carries a laminated brush 3 for engagement by a coöperating contact 4 upon an arm 5 which may be assumed to be pivotally mounted to 40 permit such engagement. The brush and the lubricating means therefor are attached by a bolt 6 to the brush holder 1 which is notched at 7 to receive the same, and which also carries an arcing contact 8 for engagement by a coöperating contact 9 carried by 45 a lever 10 pivoted at 11 upon the arm 5, these contacts being of conventional form.

The brush 3, shown in detail in Fig. 2, includes the usual body of laminæ 12 assembled flatwise and providing a contacting surface 13. The lubricating means includes a flat plate 14 bent to substantially U-shape and snugly engaging the outside laminæ of said brush but spaced an appreciable dis-

tance from the included edge thereof. This 55 space is filled by a layer 15 of felt or other absorbent medium which is retained in proper relation by one or more lugs 16 inwardly struck from the body of the plate 14. An orifice 17 extends through said plate 60 and laminæ to receive the bolt 6 which thus serves to clamp the said members together while attaching the ensemble upon the holder 1. A similar orifice 18 is also provided in the plate 14 for permitting attachment 65 of the same upon said brush in reverse relation.

In practice, the absorbent pad 15 is saturated with a suitable lubricating fluid, which by reason of capillary attraction or 70 other action slowly feeds through the interspaces of the laminæ until it finally reaches their contacting surface 13 thereby lubricating the same as well as the coacting surfaces of the laminæ. The brush being 75 thus lubricated, acts further as a conveyer to transfer the necessary quantity of lubricant to the flat contact 4 during its engagement therewith, thus minimizing the erosion of the latter incident to switch operation. 80

What I claim as new and desire to secure by Letters Patent is:

1. A switch having coöperating contacts, one a laminated brush, a plate associated with said brush and having a portion overlapping a laminated edge thereof, a lubricant absorbent pad held within the overlapping portion of said plate and in intimate contact with said brush, a brush holder, and a bolt extending through registering openings in said plate and brush for clamping the same upon said holder, said plate being provided with a second opening for the purpose set forth. 85

2. In a switch mechanism, in combination, 95 a pair of coöperating contacts, one of said contacts comprising a laminated brush, a brush holder notched to receive the same, means associated with said brush for lubricating the contacting surface of the same 100 whereby lubricant is also conveyed to said coöperating contact, and a bolt extending through said brush and associated lubricating means for clamping the said parts in operative relation upon said brush holder. 105

In witness whereof, I have hereunto subscribed my name.

CLARK T. HENDERSON.
